UNITED STATES PATENT OFFICE.

CHARLES E. KIELLEY, OF SUPERIOR, WISCONSIN, ASSIGNOR OF TWENTY-FIVE AND ONE-HALF PER CENT TO JOHN L. McMAHON, OF MILWAUKEE, WISCONSIN, AND TWENTY-FIVE AND ONE-HALF PER CENT TO FRED O. BRANDT, OF ST. PAUL, MINNESOTA.

RAIL SHAPER.

Application filed February 21, 1925. Serial No. 10,835.

This invention relates to railroad rail shaping devices and has special reference to novel means for forming notches in the lower opposed corners of the bulb of a railroad rail upon which portable superstructures are supported, such for example as dock cranes, or the like, and which are provided with rail clamps or holding devices notched for cooperation with such rails.

10 The principal object is to produce a practical and simple device for the economical and uniform shaping of such a rail, and one that may be readily adjusted so as to be applicable to various sized rails.

15 Other objects and advantages of the invention will appear in the further description thereof.

20 Referring now to the accompanying drawings, forming part of this application, and in which like reference characters indicate like parts:

25 Figure 1 is a side elevation of one embodiment of my improved rail shaper as applied to a railroad rail;

Figure 2 is a top plan view; and

30 Figure 3 is a central transverse section on the line 3—3, Figure 2.

35 1 represents an ordinary steel railroad rail, and 2 is the body portion of the shaper carriage which is superimposed upon the rail; this carriage comprising an elongated narrow metal member supported at either end upon a roller 3, the journals of which are shown at 4, within laterally extending brackets 5, upon either side of the lower corner of the member 2; this being to permit of as wide a tread roller 3 as possible, the same being preferably approximately the same width as the body member 2.

40 Upon either end of the body portion 2 of the carriage are upwardly extending brackets 6, they being somewhat triangular in shape from an end view of the carriage and having in the uppermost extremity the shaft 7, while in their lateral extremities are journalled two like shafts 8 and 9. The shaft 7 is that which transmits power to the shaper from a source of supply which may either be manual or by means of any form of motor either directly connected or otherwise, though I have simply shown a crank 10 as representing such adaptation. This crank is shown as applied directly to the large disc or gear 11, which, as is obvious, may be so

constructed as to receive action from other forms of power than the crank. On the opposite end of the shaft 7 is mounted a small spur gear 12 which meshes with the larger gear 13 keyed to the shaft 8 externally of the bracket 6, the same being for the rotation of said shaft as well as the shaft 9, the cooperative action of which will be described later.

55 Slightly to one side of the middle of the carriage body 2 are rigidly attached thereto two upright spaced members 14, the shaft 7 rotatively passing through said members. These members 14 act as guideways for the pivotally united members 15 and 16 which are so united centrally as at 17, and their 60 pivotal pin is extended sufficiently to be guided within the slot 18 in the members 14. There are two members or links 16, one upon either side of the member 15, and the links 16 are pivotally connected as at 19 to the 65 upper end of the cradle 20, while one end of the member 15 is pivotally united as at 21 to the cradle 22. The opposite end of the member 15 is arched upwardly, overreaching the pivotal connection 19 of the links 16 and 70 cradle 20 and extends outboard of same as a manipulating handle, indicated at 23. To this handle, just outwardly of the pivotal connection 19 is pivotally supported as at 24 the depending link 25 carrying an externally 75 screw threaded rod 26 passing through the slotted lug 27 projecting from the upper end of the cradle 20, and said rod being provided with the adjusting nut 28 provides convenient means for raising and lowering the 80 pivotal point 17, thus drawing together or separating the upper ends of the cradles 20 and 22.

85 These cradles are pivotally mounted, one upon the shaft 8 and the other upon the shaft 9, and the upper extremities of the cradles are of single wide construction having a bearing the full width thereof on their respective shafts, while their lower ends comprise two spaced leg-like members 29 on 90 the cradle 20 and 30 on the cradle 22.

95 These leg-like members normally extend downwardly and are inclined inwardly towards and below the bulb of the rail 1. Intermediate of each pair of legs is carried 100 upon the shafts 31 and 32 a tap-like cutter 33. Each shaft 31 and 32 is provided with a double train of gears, one upon either side of

each cradle, such gears being numbered 34, 35, 36 and 37, the trains or sets being identical and are used in multiple in this manner to provide stability and evenness of driving power. The gears 37 on the shaft 8 and like gears on the shaft 9 are made of the proper diameter to intermesh so that one pair drives the other at a uniform rate of speed, they both deriving their power from the shaft 8.

Upon what I choose to call the rearmost end of each shaft 31 and 32 is keyed a worm 38 which is of a suitable diameter to snugly mesh within the finished notches 39 formed upon the lower corners of the bulb of the rail 1 when the cutters 33 are in operating position against the bulb of the rail, and which position as is obvious is determined by the linked connection just described of the upper ends of the cradles 20 and 22. Now it will be observed that if the large gear 13 keyed to the shaft 8 imparts a clockwise rotation to the shaft 8 as viewed from the front of the machine the same will rotate the cutter or tap 33 on the shaft 31 in an anti-clockwise direction, and the two gears 37 being in mesh as previously described will result in the other tap 33 on the shaft 32 being rotated in a clockwise direction. That is to say both taps will impart an upward cutting action against the bulb of the rail, and, each being tap like in form with helical cutting teeth flat or substantially so in the front end of the tap and finished full depth in the rear, each tooth will cut its respective depth as the device is advanced by the worms 38, they rotating as is obvious at the same speed as the taps and in the finished notches made by said taps.

The taps 33 differ from an ordinary thread forming tap as used in making cuts or the like in that the clearance ways or channels longitudinally of the tap are slightly spiral in form as clearly indicated in Figure 1 of the drawings. This is done as is obvious for the purpose of avoiding chatter and jumping of the taps by the continuity of the cutting process due to the spiral form of the clearance channels.

There is illustrated at 40 a transverse reinforcing bar or member, it being mounted securely upon the upper edge of the body portion 2 of the carriages, and through the opposite ends of which the shafts 8 and 9 extend, forming an additional journal and bearing for same. Intermediate of this auxiliary bearing and the bracket on the front end of the carriage is swingingly journaled as in the depending bracket 41 from the shaft 8 a vertically disposed cutter shaft 42, carrying upon its upper end and just beneath the shaft 8 a miter gear 43 meshing with the similar gear 44 keyed to the shaft 8, and upon its lower end a tapered cutter

head 45. This cutter head is for planing the side edge of the bulb of the rail as the shaper is passed therealong. Upon the shaft 9 is an identical cutter head and the two brackets 41 of which are held together as by the through bolt 46 having adjusting nuts 47 thereupon externally of each bracket, so that the adjustment of the brackets laterally may be accomplished to a nicety and resulting in a uniform sizing of the bulb of the rail prior to being operated upon by the notch forming taps, and it is also obvious that the lower corners of the bulb of the rail must be chambered by hand or otherwise for the initial starting of the device.

While I have shown the bolt 46 and nuts 47 as a simple means of adjustment for the bracket 41 it is evident that the bolts may be dispensed with and a link mechanism identical with that for similarly adjusting the taps be employed above the brackets 41.

Just inwardly of the bracket 6 at either end of the shaper is a pair of depending laterally adjustable arms 48, one suspended from each of the shafts 8 and 9, and in the lower end of the each of these arms is rotatably mounted a guiding roller 49, it having an extending flange 50 about the lower end of same, the latter being engageable beneath the lower corner of the bulb of the rail and the thread thereof engageable against the side of the bulb, they being for the proper guiding and supporting of the shaper upon the rail. Furthermore each pair of the arms 48 are made laterally adjustable by a bolt 51 and suitable nuts 52 similar to the manner in which the depending brackets 41 are made adjustable.

From the foregoing it is apparent that I have devised an exceedingly simple and compact shaper for the forming of a series of notches upon the lower outer corners of the bulb of a rail in preparing the same for use in connection with the rail clamps equipped for such engagement; such a clamp being fully disclosed in my copending application Ser. No. 730,936. While I have illustrated one practical embodiment of the invention such as has already been employed it is apparent that various modifications may be resorted to without departing from the scope of the following claims, it being understood that the device may be used as a planer only in restoring a deformed rail to uniform size, or that any one or more of the four corners of the bulb of the rail may be shaped, as desired.

Having thus described my invention, what I claim and desire to secure by Letters Patent, is:

1. The combination with a rail shaper of the character described having means for initially uniformly sizing the bulb of the rail, an elongated tap engageable with the

5 rail upon either side thereof for forming notches in the lower outer corner of the bulb of the rail, and means cooperatively connected with the taps and engageable within the notches formed by same for feeding the shaper.

2. The combination with a rail shaper of the character described having means for initially uniformly sizing the bulb of the

10 rail, an elongated tap engageable with the rail upon either side thereof for forming notches in the lower outer corner of the bulb of the rail so constructed as to uninterruptedly cuttingly engage the rail during the operation of the shaper.

15 In testimony whereof I hereunto affix my signature.

CHARLES E. KIELLEY.
